UNITED STATES PATENT OFFICE.

NORMAN W. CUMMINS, OF BRIDGEPORT, CONNECTICUT, ASSIGNOR TO THE BURNS & BASSICK COMPANY, OF BRIDGEPORT, CONNECTICUT, A CORPORATION OF CONNECTICUT.

GREASE-CUP.

1,233,648.

Specification of Letters Patent. Patented July 17, 1917.

Application filed April 2, 1917. Serial No. 159,242.

To all whom it may concern:

Be it known that I, NORMAN W. CUMMINS, a citizen of the United States, residing at the city of Bridgeport, county of 5 Fairfield, State of Connecticut, have invented certain new and useful Improvements in Grease-Cups; and I do declare the following to be a full, clear, and exact description of the invention, such as will enable others 10 skilled in the art to which it appertains to make and use the same.

This invention relates to certain new and useful improvements in grease cups, and more particularly to a rotatable closure 15 therefor, and it has for an object to provide a simple and efficient closure cap construction without the use of washers, rivets, screws, or other extra parts.

The invention consists of an inner cap 20 and an outer cap positioned over the former and extended below or beyond the same, the outer cap being then crimped or turned inwardly so as to leave a space between the crimped end of the outer cap and 25 the marginal edge of the inner cap, within which space is confined a spring element. By this construction, the outer cap is held from removal and in close fitting relation with the inner cap to thereby exclude dirt 30 and foreign matter from entering between the caps.

Therefore, the invention further resides in the provision of a rotatable closure for 35 grease cups, and other receptacles, which will be dust-proof without the addition of washers.

Further, the invention resides in the features of construction hereinafter described in detail, and succinctly claimed, reference 40 being had to the accompanying drawing wherein

Figure 1 is a side elevation of the improved grease cup;

Fig. 2 is a top plan view thereof;

Fig. 3 is a vertical section through the cup on line 3-3 of Fig. 2; and

Fig. 4 is an edge elevation of the coiled spring employed in the improved construction.

Referring more in detail to the drawing and using like characters of reference for corresponding parts, the numeral 1 designates the grease cup body having the discharge nipple 2 in which is arranged the 55 vertical steel tube 3 for containing the wick

4 and the braided wire 5, all of which is well known and common in lubricators of this type.

The closure, constituting the subject matter of the present invention, comprises an 80 inner cap 6 which is tightly and securely fixed on the upper end of the cup body by friction, the peripheral flange of the cap embracing the exterior of the body so as to present the lower marginal edge or shoulder 65 7 outside the body. An outer cap 8, having an internal contour similar to the exterior of the inner cap 6, is mounted thereon so as to revolve freely and embodies peripheral flange 9 that extends down below 70 the lower marginal edge 7 of said inner cap. As is clearly depicted in Fig. 3, this extended flange 9 has its lowermost edge inturned or crimped to provide a shoulder 10 that is spaced from, but opposes, the marginal 75 edge 7. A resilient element is interposed in the space between the opposing surfaces or shoulders, and said element in this instance consisting of a coiled spring 11, which may embody but a single coil, one terminal bearing upwardly against the shoulder 7 and the other terminal exerting a downward pressure on the shoulder 10.

By this construction, the outer cap is readily rotatable and retained in any position by the spring; the spring keeps the opposing faces of the caps close together to exclude dust and dirt; and no additional parts, such as a central rivet, are required to pivotally connect the caps. There is no 85 actual connection between the inner and outer caps and, consequently, the assembling and mounting of the closure is greatly facilitated and may be expeditiously and 90 economically accomplished.

The caps are provided with coinciding filling openings 12 and 13, the cap 8 being relatively rotatable to register the openings or to displace them, the coiled spring element serving to retain the outer cap in a 100 predetermined position.

The closure comprises only three parts, all of which are metal. No washer or other packing is required between the caps since the spring holds said relatively conforming 105 caps closely together. The parts may be assembled either on or off the cup body, the inner cap being pressed on into frictional engagement with the body, embracing the exterior of the latter.

What is claimed is:

1. In combination with a cup body, an inner cap having a peripheral flange frictionally embracing the exterior of the body, an outer cap having its inner surface conforming to the outer surface of the inner cap, said outer cap also having a peripheral flange extending below the marginal shoulder of the flange of the inner cap and crimped inwardly to form a shoulder opposing the aforesaid shoulder of the inner cap, and a coiled spring interposed between the opposing shoulders to hold the inner and outer caps closely related, said caps having registerable openings for the insertion of a lubricant.
2. A closure for grease cups comprising an inner cap having a marginal shoulder, an outer cap rotatable on the inner cap and extending beyond the latter, said extended part being inturned to provide a shoulder opposing the first shoulder, both caps having registerable openings, and a coiled spring interposed between the opposing shoulders of the caps. 20 25

In testimony whereof I affix my signature in presence of two witnesses.

NORMAN W. CUMMINS.
